UNITED STATES PATENT OFFICE.

NORMAN E. ZUSI, OF NEWARK, NEW JERSEY, ASSIGNOR TO MEISSELBACH-CATUCCI MFG. CO., A CORPORATION OF NEW JERSEY.

HOBBING SPECIAL-SHAPED TOOTHED GEARS.

1,104,859.

Specification of Letters Patent. Patented July 28, 1914.

Application filed December 14, 1912. Serial No. 736,683.

To all whom it may concern:

Be it known that I, NORMAN E. ZUSI, a citizen of the United States, residing in the city of Newark, county of Essex, and State 5 of New Jersey, have invented certain new and useful Improvements in Hobbing Special-Shaped Toothed Gears, of which the following is a specification.

Hitherto, it has been the practice of gear makers to mill the teeth of such special forms as ratchet wheels, timing and carrying wheels for adding machines and cash registers, etc., but so far as I am aware no attempt has been made to cut such gears 15 by the hobbing process. It is well known that the milling process as applied to gear cutting often results in imperfect gears, because of inaccuracy in indexing due to the dulling of the cutter before the work is completed, the inaccuracy of feeding the work to the cutter and many other reasons which are either impossible or at least 20 hard to account for. For these reasons the manufacture of regular shaped gears is being done more and more extensively by the hobbing process as its capabilities become 25 more fully developed.

In the patent to Pliny Catucci, No. 978,113 dated Dec. 6, 1910, is shown and described 30 a gear cutting machine designed for cutting gears with regular or standard teeth, by means of a hob of the usual type, and my invention has specific reference to said patent, and to the machine described therein, al- 35 though it is to be understood that my special forms are capable of use in other hobbing gear cutters, and my process may be carried out with other instrumentalities.

When a particular form of gear, ratchet 40 or other special toothed gear has been decided upon, the problem is to determine the exact form of the cutting edge of the hob tooth which will produce such special toothed gear. In the solution of the problem 45 I have assumed the exact shape and number of the teeth in a particular wheel, and proceed from such shape to generate the shape and form of the cutting edge of the hob tooth which will produce such special form 50 of tooth, so that the resulting teeth shall all be accurate in shape and form, and the so called "fat tooth" in the gear shall be avoided.

The object, therefore, of my invention is 55 to produce a special shaped hob and to de-

velop the process by which such hobs may be formed.

In the accompanying drawings I have shown diagrammatically the method of developing the shape and form of two such 60 special forms; but I wish to be understood as in no wise confining this development to these forms alone. The forms selected are, each extreme in its own direction, and in practice have proven the most difficult of 65 all to produce. The development of the special forms shown will readily suggest to the designer the method of extending the process to any desired form of special tooth.

In the drawings, Figure 1 illustrates dia- 70 grammatically several retrogressive pos- tions of a ratchet tooth, the face of which is radial and the back of which is straight, in connection with the corresponding pos- 75 tions of the edge and point of a hob cutter, designed to cut pointed ratchet teeth. Fig. 2 illustrates diagrammatically the super- 80 posed relative positions of the retrogressing ratchet tooth, showing the method of developing the curve of the cutter tooth to generate the straight back of the ratchet tooth. Fig. 3 illustrates the application of the proc- 85 ess to the determination of the shape of a hob cutter tooth to produce what is known in the art as the double tooth ratchet. Fig. 4 90 illustrates an end view of a hob cutter de- signed for cutting the straight backed ratchet tooth. Fig. 5 illustrates a side view of the same. Fig. 6 illustrates a sectional view of the ratchet toothed hob cutter and 95 relative position of a single ratchet wheel. Fig. 7 illustrates the end view of a double toothed ratchet hob cutter. Fig. 8 is a side view of the same. Fig. 9 is a sectional view 100 of the double ratchet hob cutter showing also the relative position of the double ratchet. Fig. 10 is a partial side elevation of the hobbing gear cutter of Pliny Catucci's Patent No. 978,113, showing the method of cutting a gang of blanks.

Similar letters of reference refer to like parts throughout the specifications and drawings.

In the development of the process for laying out the shape of the cutting edge of a 105 hob for cutting the radial face straight backed single ratchet, reference is made to Figs. 1 and 2. In Fig. 1, let 0, 1, 2, 3, 4, 5, 6, 7, 8, 9, 10, be the retrogressive positions of the point of a ratchet tooth upon the 110

wheel and $0'$, $1'$, $2'$, $3'$, $4'$, etc., be the corresponding positions of the roots of such teeth, all of which are located upon the pitch circle $X Y$ of the ratchet. The face of the 5 ratchet tooth is assumed to be radial as $0 N$. Let the two lines $P Q$ and $R S$ be assumed respectively as the pitch line and the locus of the progressive points of the tooth of the cutter. From the point $0'$ on the pitch- 10 circle of the ratchet wheel, lay off on the line $R S$ the points $1'', 2'', 3'', 4'', 5'', 6'', 7'',$ etc., making their distances apart equal to $0'$, $1', 1', 2'$, etc. Erect a perpendicular at each 15 of the points including the perpendicular from the point $0'$, which in this case is also the vertical radius of the ratchet wheel. If now the ratchet wheel is assumed to revolve upon its center in the direction of the arrow, while the locus line $R S$, travels in the same 20 direction and tangent to the pitch circle $X Y$, at the extremity of the vertical radius, the root of the tooth $0', 1', 2', 3', 4'$, etc., will correspond successively to the points $1'', 2'', 3'',$ etc.; in other words the point $0''$, 25 $1'', 2'',$ etc., may be assumed as retrogressive positions of the point of the tooth of the rotating hob cutter corresponding to the retrogressive positions of the root of the ratchet tooth $0', 1', 2'$, etc.

30 Referring now to Fig. 2; lay off line $P Q$ and $R S$ respectively as the pitch line and the locus of points of the teeth of the cutter respectively. Lay off upon the line $R S$ the distance $D E$ as the exact pitch of the 35 ratchet, in this case $0' N$. Erect $D F$ and $E G$ perpendicular to the line $R S$ at the points D and E respectively. The entire cutting edge of the hob cutter tooth will now 40 be contained in the rectangle $D E G F$ and the perpendicular $D F$ may be assumed to be that portion of the cutter tooth which will generate the radial face $0 N$ of the tooth of the ratchet.

From a reference to Fig. 1 it will readily 45 be seen that a point of the cutter tooth will come only in contact with the root of the ratchet tooth, when such point and root coincide at $0', 0''$. From the point we draw a line $D O$ parallel to the back of the tooth 0 , 50 in other words, draw the tooth 0 complete as it appears above the pitch line $R S$. Next draw the tooth 1 superposing the same on Fig. 2 and making the back of such tooth in the same relative position to the point D , 55 that such tooth occupies in Fig. 1 with respect to the perpendicular from the point $1''$. Next superpose upon Fig. 2 the tooth 2 making it occupy the same relative position with respect to D , that it occupies in Fig. 1 60 with respect to the point $2''$. Next superpose upon Fig. 2 the tooth 3 making it occupy the same relative position with respect to the point D that the tooth 3 occupies with respect to the point $3''$ in Fig. 1, and so on, 65 superposing each of the relative positions of

the teeth $4, 5, 6, 7, 8, 9, 10$, in Fig. 2 making such teeth occupy the same relative positions with respect to the point D that they occupy in Fig. 1, with respect to successive points $4'', 5'', 6'',$ etc. If now the curve is struck through the points of the teeth in Fig. 2 such curve will correctly delineate the locus of the point of the ratchet tooth with respect to the advancing cutter tooth, but since we are only interested in the generation of the back of the tooth it will be readily seen that the backs of the superposed teeth in Fig. 2 form the envelop of the curve, drawn from the point D and running into the locus of the point of the tooth, it will also be seen the 75 positions of the ratchet tooth at 10 and 9 are entirely within this envelop; that the tooth at 8 apparently is tangent to the curve of the envelop, and that beyond S the envelop and the locus coincide. The curve of this 80 envelop therefore determines the curve of the cutting edge of the hob tooth to generate the straight back of the ratchet tooth. By referring to the locus of the point of the tooth at 7 in Fig. 2 it will be seen that in this 85 position the tooth merely touches the envelop at this point. The same is true of the positions 5, 4, etc. The envelop only touches the back of the tooth when it is in positions 90 7, 6, 5, 4, etc. The back of the ratchet tooth 95 begins to generate in its true form at the point where the locus of the advancing tooth coincides with the envelop curve and from that point the back of the tooth may be assumed to roll upon the envelop curve up to 100 the point D . In practice, therefore, it is only necessary to continue the envelop curve up to the point where such curve unites with the locus of the point of the tooth, and such curve may then be continued right on up as 105 shown in Fig. 2 to the line $P Q$ so that after the point of the tooth leaves the curve it is entirely free from contact with the cutter. This is as it should be, for after the point of 110 the tooth has been generated, there is no necessity for further mechanical operation upon it. The continuation of the enveloping curve to the pitch line $P Q$ also overcomes the mechanical difficulty of forming the curve in the cutter tooth accurately beyond 115 the point where the curve and the locus of the tooth point coincide. In other words, by cutting away the metal between the point H , and the point G , plenty of clearness is left for the progressive travel of the point of 120 the ratchet tooth.

We have, therefore, the curve $D H$ as the correct shape of that edge of the cutter tooth which will generate a straight backed ratchet tooth. The edge of the tooth which generates the radial face $0 N$, of the tooth must obviously coincide with such radial face at the vertical radius $0' C$, at which point the very last shaving of metal is removed and the face is completed. The con- 125 130

tour F D H is, therefore, the exact shape of the cutter tooth which will completely generate the ratchet tooth O N O'. Fig. 2 further discloses an important principle in my invention which is as follows: It will be noted that the path of the ratchet tooth after it crosses the vertical line G E intersects the parallelogram P G E R, which would be the parallelogram which would include the cutting edge of the next tooth in the helix of the hob. If such tooth were upon the hob, it is readily seen that the tooth just formed by the cutter tooth F G H would be completely destroyed. It is, therefore, necessary that the last cutter tooth on the hub should be located at a point where the point of such cutter tooth D coincides with the root of the tooth O'. In order that the shape of the tooth may be preserved, this feature will be explained, hereinafter, in the specific description of the hob itself.

The above description of the generation of the contour of the hob tooth applies to one of the extreme forms of my invention. The other extreme is the form of the hob tooth designed to generate what is known as the double ratchet. All other forms of gear teeth may be included between these two extremes. In the generation of the form of cutter tooth to cut the double ratchet, the same process of retrogressive super-position of a contour of the tooth upon the wheel to be cut is utilized for determining the contour of the cutting teeth. Inasmuch, however, as this process of retrogressive super-position has been fully explained above, it is deemed unnecessary to repeat it with special application to the form of cutter tooth to cut the double ratchet. In this case, the contour of the cutting edge of the tooth instead of being a curved envelop becomes a broken line.

Reference is now made to Fig. 3. In this case the sides of the double ratchet tooth, instead of being radial are tangential to a circle which is concentric with the center of the ratchet. For example, the faces of the teeth 20 and 21 are tangential to the circle 22. As above explained, the reason set forth above for locating the last tooth of the cutter in the vertical radius applies in the present case and the shape of such tooth must be substantially the shape of the notch between the adjacent teeth of the ratchet. Inasmuch as the last tooth of the cutter removes the final shaving which completes the faces of such teeth, we may start with a cutter tooth whose cutting edge is substantially the shape of this notch or groove. Let 24 be such cutter tooth. If now that tooth be located axially upon the vertical radius 25, 26 of the double ratchet, it will appear as shown in Fig. 3 with the vertical edges of such cutter tooth coinciding with the sides of two adjacent ratchet

teeth 20 and 21. The pitch of the cutter and the pitch of the double ratchet will obviously be the same, but it is noted from a reference to Fig. 3 that with the tooth 24 in the position shown the corresponding tooth 27 in the next helix of teeth on the cutter would interfere with or cut away a portion of the material which would form the tooth 21, unless some special provision were made, to avoid such cutting away. I provide for this by changing the pitch of the cutter teeth upon one side, so that it will not interfere with the adjacent point of the ratchet tooth 21 as clearly shown in Fig. 3. Now since the cutter is revoluble we have the exact shape of the tooth 24 and the tooth 27 as being the corresponding teeth in successive helices upon the cutter. All of the teeth surrounding the helix, of which tooth 24 is the first tooth, will gradually vary in width until such helix runs into the helix of which tooth 27 is the first tooth; theoretically the next tooth 28 of the cutter would be correspondingly reduced in thickness and the tooth in the helix of which 27 is the first tooth would gradually diminish in thickness around the body of the cutter until they approach the thickness of tooth 28; but in practice only about two helices of teeth on the cutter are active, so that the tapering of the helix of the teeth need not be carried beyond the second or third helix.

Inasmuch as the tooth 24 is the last to act upon the groove between the teeth 20 and 21 it is quite obvious that, because of the faces of such teeth 20 and 21 being tangent to the circle 22, the cutting edge of the tooth 24 would not cut completely down to the root of the tooth 21. This is quite clearly shown by the fact that the point line of the cutter teeth is tangent to the pitch circle of the ratchet. If it is necessary that this slight excess of material be removed that the ratchet may operate successfully the cutting edge of the tooth 24 may be extended out so that its lower cutting edge will coincide with the pitch line of the ratchet. I have shown this more fully in connection with the cutter tooth 27, where the outline at the point of the tooth, as at 29, illustrates the exact shape of the tooth, to remove the slight portion of metal located right at the root of the advancing tooth of the ratchet. In practice, however, this would form no obstacle to the usual operation of the ratchet tooth and the points of all of the teeth in the cutter may coincide with the surface of an enveloping cylinder.

In Figs. 4 and 5 I have shown the form which a hob cutter for cutting straight backed single ratchets will take. It will be observed in Fig. 5 that the tooth 30, is the last cutting tooth of the helix which is designed to remove the very last shaving of a tooth such as 31, (Fig. 6) and to form 180

the radial face 32 of the next tooth. Ordinarily the helix of a hob cutter has been continued around until it runs off the cylindrical body of the cutter, and for some distance around the helix the teeth do not have a full or complete contour; but as above indicated in order to preserve the point of the teeth it is necessary that the teeth beyond tooth 30, which is the first one of the helix 10 which has a full or complete contour, be removed from the cutter body and left blank as at 33 upon the body of the cutter, as shown in Fig. 5.

In Figs. 7 and 8 I have shown the form 15 of the cutter designed for generating the double ratchet as shown in Fig. 9. It will be observed in this case that tooth 34 is the last cutting tooth of the helix of teeth and that as the helix progresses around the cylindrical body they are successively narrower, for the reason above stated. It is understood that the tooth in advance of tooth 30 and tooth 34 serves the purpose of removing the shavings of metal from the 20 blanks but that it is in each case the last tooth as 30 or 34 which removes the very last shaving of metal to complete the form of the back of one tooth and the face of the next successive tooth.

30 In the practice of my invention a plurality of disks 35 is mounted upon and firmly secured to a mandrel 36 and the mandrel is then mounted between the centers of the hob cutting machine, for example, that 35 shown and described in the above named patent to Pliny Catucci. The cutter 37 is mounted upon the cutter shaft 38 which is in turn carried in the bearings 39 of the vertical stanchion 40. The cutter shaft 38 may 40 be raised and lowered by means of a vertical feed screw 41 which is operated by means of the crank 42. The mandrel 36 is rotated at a predetermined speed by means of the change speed gears 43 and the vertical stanchion 40 is fed by the proper feeding mechanism 44 as fully described in the above named patent to Pliny Catucci. However, the cutting machine forms no part of my invention and I have only illustrated so much 50 of the cutting machine of the Catucci patent to show the method of using all forms of hob cutters, as may be necessary to gain a full understanding of the same.

In each of the specially constructed hobs, 55 it will be noted that the cutting edges of the teeth are in radial planes; that is to say, all lie in planes which pass through the axis of the cutter; and that the backs of such teeth are relieved; that is to say, the backs of the 60 teeth lie in circles, each of which is eccentric to the pitch line of the teeth. By so constructing them, the radial sections of the teeth are always the same, so that the teeth may be sharpened by running a special 65 shaped grinding wheel in the grooves which

separate the successive teeth in their respective helices.

It will thus be seen that I have developed a new process for generating the teeth of a hob gear cutter for cutting special toothed gears, and this process consists generally in assuming the shape of the tooth of the special gear and then proceeding retrogressively with various positions of the tooth, so as to form a corresponding series of superposed tooth contours, and through such a series of contours the enveloping curve or broken line as the case may be is delineated. This enveloping curve must therefore be the correct shape of cutting edges of the helical row of teeth upon the hob cutter. The final step consists in removing all of the teeth of the last helix excepting that which takes the last shaving from, and develops the final shape of the tooth of the special gear. In practice the work piece is set with special regard to this last tooth, as tooth 30 of the straight backed single ratchet, or tooth 34 of the double ratchet wheel.

I have not shown those forms of cutter 90 teeth which would come between the extremes shown in the drawings and described above, as it is obvious that the correct form of cutter tooth may be readily developed, when only the special form of the tooth 95 upon the wheel is known.

I claim:

1. A hob cutter having a cylindrical body with a helical row of cutting teeth upon said body, said helical row beginning with the first tooth having the contour of its cutting edge complete.

2. A hob cutter having a cylindrical body, and a helical row of cutting teeth thereon, said row beginning with the tooth whose cutting edge is of complete contour and whose cutting edges lie in radial planes.

3. A hob cutter having a cylindrical body and a helical row of cutting teeth thereon, the first tooth of which is of complete contour, said row of teeth varying in contour progressively throughout the helix from said first tooth.

4. A hob cutter having a cylindrical body and a helical row of teeth, with the contours of the cutting edges of said teeth varying progressively throughout the length of the helix.

5. A hob cutter for cutting ratchet teeth having a cylindrical body and a helical row of teeth thereon, the contour of whose cutting edges is determined by the envelop line generated by the retrogressive super-position of a complete ratchet tooth of the form to be cut relative to the corresponding position of some definite point in the cutter tooth.

6. A hob cutter for cutting ratchet teeth having a cylindrical body and a helical row of teeth thereon, the contour of whose cut-

ting edges is determined by the envelop line generated by the retrogressive superposition of a complete ratchet tooth of the form to be cut, relative to the corresponding position of some definite point in the cutter tooth, said helical row of teeth beginning with a tooth, the contour of whose cutting edge is full or complete.

7. A hob cutter having a cylindrical body and a helical row of cutting teeth thereon, the cutting edges of which lie in radial planes, and having all mutilated or incomplete teeth removed from said cylindrical body at the beginning of the helix.

8. A hob cutter having a cylindrical body 15 and a helical row of teeth thereon, said row beginning with a tooth whose cutting edge is theoretically correct in contour as determined by the teeth of the wheel to be cut and lies in a plane radial to the cylindrical 20 body.

In testimony whereof I have hereunto set my hand this 6th day of December, 1912.
